(57) CLAIM

The ornamental design for a body suit, as shown and described.

DESCRIPTION

FIG. 1 is a front perspective view of a body suit, showing my new design, shown in use;

FIG. 2 is a front elevational view thereof;

FIG. 3 is a rear elevational view thereof;

FIG. 4 is a side elevational view thereof;

FIG. 5 is a top plan view thereof;

FIG. 6 is a bottom plan view thereof; and,

FIG. 7 is a rear perspective view of a body suit, shown in use.

The broken lines shown in the drawings view are for illustrative purposes only and form no part of the claimed design.
